CABINET FOR A BATH SPRAY OR SIMILAR ARTICLE

John E. Svabek, Jr., Westchester, and Nicholas P. Arvan,
Berwyn, Ill., assignors to Crane Co., Chicago, Ill., a
corporation of Illinois

Filed Feb. 16, 1968, Ser. No. 10,606

Term of patent 14 years

Int. Cl. D6—01

U.S. Cl. D33—21

*Fig. 2.**Fig. 4.*FIGURE 1 is a perspective view of a cabinet for a bath spray or similar article showing our new design; FIGURE 2 is a front elevational view thereof showing the door in an open position.

FIGURE 3 is a plan view thereof; and

FIGURE 4 is a side elevation thereof.

The broken line representation of a bath spray and hose assembly in FIGURE 2 is for purposes of illustration only. FIGURES 1 and 2 are shaded to show texture of the planar surface.

We claim:

The ornamental design for a cabinet for a bath spray or similar article, as shown and described.
